UNITED STATES PATENT OFFICE.

MIRON G. TOUSLEY, OF MENDOTA, ILLINOIS, ASSIGNOR TO DIEBOLD & KIENZLE, OF CINCINNATI, OHIO.

IMPROVEMENT IN SPINDLES FOR SAFE-LOCKS.

Specification forming part of Letters Patent No. 118,830, dated September 12, 1871.

To all whom it may concern:

Be it known that I, MIRON G. TOUSLEY, of Mendota, in the county of La Salle and State of Illinois, have invented a new and useful Improvement in Safe-Lock Spindles; and I do hereby declare the following to be a full, clear, and exact description thereof, which will enable others skilled in the art to which my invention appertains to make and use the same, reference being had to the accompanying drawing forming part of this specification, in which—

Figure 1 is a transverse longitudinal section of a portion of the walls of a safe with my improvement attached thereto, cutting the same through the center. Fig. 2 is a cross-section of the spindle on line *x x*. Fig. 3 is a detached section of a portion of the key employed in turning the spindle, and Fig. 4 is a vertical longitudinal section of a portion of the safe-walls, with dial removed, showing the manner of closing the aperture within which the key for turning the spindle is introduced.

Similar letters of reference indicate corresponding parts in the several figures of the drawing.

The nature of my invention consists in so constructing the key in connection with a loose plug and the lock-spindle as to operate in combination, when arranged as hereinafter described; also, in so arranging the inner portion of the spindle as to ignite a fuse secured therein when force is applied upon its outer end to drive the same inward from the door, by which means an alarm is given.

In the accompanying drawing, A represents the dial, which may be made in the usual form. B is the key, the shank of which is secured to said dial in the ordinary manner. C is a steel plug, which is secured within an annular cavity or aperture in the outer end of the spindle D. The outer end of said plug is provided, at opposite sides, with longitudinal slots cut obliquely across the end, forming a wedge-shaped center. Into this slot I introduce the blade *d* of the key for turning the same, said blade being cut away or fork-shaped, forming in its end a recess approximating said wedge-shaped center in the end of the plug. I provide said plug with a longitudinal groove or channel, within which is secured a feather key, *b*, that engages with and takes into a corresponding groove or channel upon the inner side of spindle D, by which means said

spindle is revolved or turned upon its bearings by the action of said dial. I secure in the outer end of said spindle a set-screw, *e*, so arranged as to come in contact with and against the outer side of said plug, by which means the same is secured in proper adjustment. The inner end of said plug is cut away, reducing its diameter, and forming a nipple, upon which I secure a percussion-cap, *f*. Around said cap, and within the cavity of the spindle, is secured a fuse, *g*. Thus, should a blow be applied to the outer end of the plug (by means of any instrument introduced into the cavity for the key, when it is removed) in the attempt to force the same inward, the cap is brought against the solid end of the cavity in the spindle, exploding the same, which ignites the fuse, by which means an alarm is given and the plug discharged from the spindle. I provide the inner side of the safe-wall with an external screw-threaded disk, *E*, through which said spindle passes. Said disk has in its end an annular cavity or recess, forming a series of oblique and rectangular shoulders, *h h*, which come in contact with and against corresponding shoulders *i i* upon the spindle, by which means the same is secured in the walls of the safe. When the key with the dial is removed from the spindle I introduce into the keyhole a stopper, *j*, as shown in Fig. 4. Said stopper may be of cork or other like material, which will protect the fuse secured in the cavity of the spindle from the air or from fire. I attach the shank of the spindle to the lock in the ordinary manner; but, as the same forms no part of my invention, a description thereof is not necessary to be herein fully given.

I am aware that spindles have been previously known and used which are secured to the wall of the safe by a screw-threaded disk having rectangular shoulders and of different general shape; but the rear of the shoulders is not properly secured, and their angles produce no expansion to the disk, so the thread may be stripped and the spindle driven by the concussion of heavy blows, while with my invention the oblique shoulders of the spindle expand the disk by the concussion of a blow and are secured, rendering the same more strong and reliable.

Having thus described my invention, what I claim as new, and desire to secure by Letters Patent, is—

1. The combination of key B with its forked end, loose plug C with wedge-shaped end, and spindle D, substantially as herein described.
2. The plug C, provided with cap and fuse *f* and *g* or their equivalents, in combination with the spindle D, substantially as herein described, and for the purpose set forth.

The above specification of my invention signed by me this 29th day of October, A. D. 1870.

MIRON G. TOUSLEY.
